UNITED STATES PATENT OFFICE

2,005,471

FRUIT AND VEGETABLE JUICE FILLING
MACHINE

Stefano Pittaluga, San Leandro, Calif.

Application December 11, 1931, Serial No. 580,301

6 Claims. (Cl. 226—98)

An object of the invention is to provide means whereby cans may be automatically charged with syrup, soups, tomato juice, or tomato paste to the exact amount required to properly fill the can, practically without waste or dripping of the liquid; and whereby the work may be performed with great rapidity.

The invention comprises a machine adapted to operate simultaneously upon a plurality of cans; receiving the cans at one place, moving them in train and delivering them from the machine at another place, the liquid or syrup being introduced into the cans as the cans pass through the machine.

Another object of the invention is the provision of a revolving feed tank provided with plurality of valves that open into a can directly underneath said valve; the cans are successively delivered to and held upon a drum rotating on a practically vertical axis so that the cans are carried around with the drum, thus placing each can in position under each valve, the feed tank being mounted on a universal joint to allow the cans underneath to operate the valves at certain positions.

Other objects are simplicity and increase of production.

Machines of various sizes and containing various numbers of valves may be constructed.

Changes in the form, proportions and minor details of construction may be made within the scope of the claims without departing from the spirit of the invention.

Other objects, advantages and features of the invention may appear from the accompanying drawings, the subjoined detail description and the appended claims.

The accompanying drawings illustrate the invention.

Figure 1 is a plan view of a filling machine embodying this invention and applied to operate upon a moving train of cans, some of which are shown being fed into the machine. A fragment of the feed chute is also shown.

Fig. 2 is a side elevation of Fig. 1 showing the feed tank tilted to the correct angle to permit the cans to operate the feed valves when the machine is in operation.

Fig. 3 is a section on line x3—x3 Fig. 2 showing a plan view of the geared adjustment for the delivery and discharge conveyors.

Fig. 4 is an enlarged diagrammatical view partly in section on line x4—x4 Fig. 2 showing the drum with notches into which fits a can in each notch and the lower disc is shown underneath

said upper notched disc; the belt drive is shown along with an adjustable geared guide for keeping the cans in proper position; part of the universal joint being shown in sections; cans are shown being fed to the drum and the guards being omitted to disclose the delivery and discharge conveyors.

Fig. 5 is a fragmental plan detail view showing one of the valves.

Fig. 6 is a sectional view taken on line x6—x6 Fig. 5 showing the construction of the valve and a can in place just before the valve is opened.

Fig. 7 is a fragmental detail front view showing a can in position underneath a valve as the can is first fed into the machine.

Fig. 8 is a view analogous to Fig. 7 showing a position just as the can starts to operate the valve.

Fig. 9 is a view analogous to Fig. 6 showing the valve in open position.

Fig. 10 is a plan view of a different type of valve showing a fragment of the feed tank.

Fig. 11 is a section on line x11—x11 Fig. 10 showing the valve in position just before being opened.

Fig. 12 is a view analogous to Fig. 11 showing the valve in open position allowing the liquid to flow into the can.

Fig. 13 is an enlarged detail sectional view of the air vent and center valve stem.

Fig. 14 is an enlarged fragmental detail view partly in section showing the feed tank and drum and showing the universal joint connecting the two. A fragment of the main frame is also shown.

Fig. 15 is a fragmental plan detail view of a type of valve used for tomato paste.

Fig. 16 is a sectional view of the valve shown in Fig. 15 in closed position.

Fig. 17 is a view analogous to Fig. 16 showing the valve in open position.

The machine comprises a rotatable drum 1 rotating on a vertical axis, a delivery conveyor 2 mounted at the left front of said drum to deliver cans 3 thereto, means to cause the cans to revolve with the drum and a discharge conveyor 4 mounted at the right front of said drum to carry the cans therefrom after said cans have moved around with the drum, each can being filled with liquid during nearly one revolution of the drum.

A circular feed tank 5 rotatable on a universal joint 6 directly above said drum 1 furnishes the supply of liquid to the cans 3 through a plurality of valves 7 equally spaced therein.

Said delivery and discharge conveyors 2 and 4

may be of any desirable form and in the present instance comprise the form of discs rotating in the direction as shown by the feathered arrows, and being positioned on a level with the top of the lower disc 8 of the drum 1.

The drum 1 is fixed to the vertical shaft 9 by a set screw 9a and said shaft is mounted in bearings 10, 11 of the main frame 12 that may be fixed to a floor or foundation by bolts 13.

10 To revolve the drum a driving means comprising a motor 14 through motor pulley 15, belt 16 connecting with pulley 17 fixed to the shank 18 of the driving pinion 19 that meshes with the plate gear 20 fixed to the vertical drive shaft 21 that is provided at its top with the drive pulley 22 fixed thereto over which the driving belt 23 fits and connects to the drum 1 fitting over the belt shoulder 24 as shown in Figs. 2 and 4 of the drawings.

20 The vertical drive shaft 21 being held and rotatable in the bearings 25, 26 of the brackets 27, 28 respectively that are fixed to the main frame 12 and a bearing collar 29 keeps said shaft in alignment.

25 The delivery conveyer 2 and discharge conveyer 4 fixed to the vertical shafts 30 and 31 respectively that are journaled in the bearings 32, 33, 34, 35 of the brackets 28, 36 and 37 and are driven through the adjustable geared chained mechanism 38 comprising a chain 39 passing over gears 41, 42 that are fixed to shafts 30 and 31 respectively and meshing with the chain 39 the gear 43 that is fixed to shaft 21 which is connected by means heretofore described to the motor 14.

35 Referring to Fig. 1 guards are shown in position above the delivery and discharge conveyers comprising inner guards 44, 45 and outer guards 46 and 47 respectively.

The feed chute shown at 48 is for empty cans only, and cans of fruit that may be fed to the delivery conveyer will be fed by means not shown.

A guard 49 that circles partly around the outer edge of the drum 1 prevents the cans from dropping off the disc while the drum is in rotation.

45 As the cans are fed to the machine to be filled at the delivery end of the drum an adjustable sprocket drive mechanism 50 comprising a sprocket chain 51 that rotates over the sprocket gears 53 and 54 and the gear 53 being mounted in the slot 55 of the bar 56 which is pivoted at 57 and having an extension 58 slidably mounted in the slot 59 and a spring 60 fixed to the auxiliary frame 61 connects with the extension 58 to keep the sprocket drive mechanism in position against the cans as shown in Fig. 4.

The sprocket drive mechanism 50 is driven through gear 62 that is mounted at 63 on the bar 64 and oscillates with the extension bar 56 and meshes with gear 65 that is fixed to shaft 30.

55 The drum 1 is provided with a plurality of notches 66 equally spaced around its periphery into which the cans fit and 67 indicates the angle of the periphery between notches so that the can may ride against it and slip into a notch as the cans are being fed into the drum.

60 Fixed to the lower disc 8 of the drum 1 are sockets 68 located directly under each notch 66 that permits the bottom end of the can to fit into and which rests on the lower disc 8 thus holding the can securely while the drum rotates.

65 Figs. 1, 2, 4 and 14 show the auxiliary frame 61 and means of adjustably mounting the feed tank 5 and construction of the universal joint 6.

70 The feed tank 5 is provided with the upper

section 69 that is held integral with the tank proper by the ribs 70 and forms the upper section of the universal joint 6 and is connected to the lower section 71 that is integral with the drum 1 through the pins 72 and ring 73. A band 74 is shown that holds the pins 72 in place.

The upper section 69 is provided with a shaft extension 75 that rotates in the adjustable bearing 76 which is adjustably mounted in slots 77 of the auxiliary frame 61 by bolts 78. This construction permits the feed tank to be set at an angle and to rotate at this angle while the cans operate the valves to fill the cans with liquid.

75 Referring to Figs. 1, 5 to 9 inclusive, the valve 1 comprises a valve stem 79 having a valve 80 at its lower end and a guide 81 at its top end. The feed tank 5 is provided with a plurality of openings 82 equally spaced in its bottom into which is slidably mounted a valve seat 83 having a downwardly extended opening 84 into which is seated 20 at the bottom the valve 80. An air vent 85 is provided in the valve seat and connects with the vertical pipe 86 that allows any air to escape from the can when it is being filled. A rubber gasket 87 is shown held in place by a collar 88 that is fixed to the bottom of the tank by the screws 89.

To open the valve 80 the can 3 presses against the rubber gasket 87 which in turns raises the valve seat 83 which operates the lever means 90 comprising a lever 90a, pivoted at 90b to a bracket 90c and operable by a spring 90d that is mounted on a vertical rod 90e which is fixed to the flange 90f of the valve seat 83 to unseat the valve 80 thus permitting the liquid to flow into the can.

35 To close the valve after the can is filled a spring closing means is provided comprising the springs 91 mounted on vertical rods 92 and fixed to the valve seat 83 and a guide bracket 93 that is fixed to the bottom of the feed tank at 94 keeps the rods 92 in vertical alignment and also forms 40 a shoulder for the springs 91. To keep the valve stem 79 in alignment a valve bracket 95 is shown and forms a shoulder for a spring 96 that is interposed between the valve 80 and valve bracket shoulders 97. The operation of the valves is assisted by the feed tank rotating on the universal joint 6 as the cans are fed into the drum 1 as will be explained in the operation of the machine.

45 In Figs. 10 to 13 inclusive is shown another form of valve that may be used comprising an annular rubber gasket 98 having an annular slot 99 that fits snugly over the edge of hole 82 and a flanged sleeve 100 slidably mounted in the gasket 98. A hollow valve stem 101 is held stationary and centrally mounted in the flanged sleeve and is provided at its bottom end with a rubber washer 102 provided with a metal band 103 and held in position on the valve stem 101 by a nut 104 underneath and above the washer 102 by 105. The valve stem 101 is held stationary by bracket 106 which is fixed to the bottom of the feed tank 5 by upright rods 107.

55 To open the valve the can 3 presses the rubber gasket 98 forcing the flanged sleeve 100 upward 60 and unseating the valve thus allowing the liquid to flow into the can as shown in Fig. 12 of the drawings. After the can is removed from the position shown the valve is closed by the springs 108 that are mounted on the flanged sleeve 100 65 and held in position by the rods 109.

70 Referring to Figs. 15, 16 and 17 a type of valve is shown that may be used when feeding a tomato paste to the cans comprising an annular rubber gasket 110 having a groove 111 extending from 75

the hole of the gasket 110 to the outside to form an air vent. A flanged sleeve 112 provided with a roller 113 that acts upon the arm 114 of the valve 115 that is pivoted at 116 to the feed tank 5 as shown in Fig. 17 in open position and in Fig. 16 in closed position.

In operation the motor 14 is turned on by the operator starting the drum 1, feed tank 5, delivery and discharge conveyers 2 and 4 rotating in the directions indicated by the feathered arrows through the drive means and reduction gears heretofore described. The cans are then fed to the delivery conveyer 2 which carries the cans around through guards 44, 46 to where just before passing on to the drum disc 8 the cans are caught by belt 23 and sprocket drive mechanism 50 which carry the cans onto the drum 1 and into place in each notch 66 and pocket 68. At this point there is ample space between the valves 7 of the feed tank 5 which has been filled with liquid and the top of the can and places the can in position directly under the valve.

As the drum rotates the feed tank rotates also but on the universal joint 6 that has an upper section 69 provided with a shaft extension 75 that is adjustably mounted off the center of the machine and at an angle causing the feed tank to converge as it rotates forcing the top of the can to force the valve 7 open allowing the liquid to flow into the can.

The timing of the machine is so regulated by the operator that each can is filled to its proper height at the time set allowing no leakage of the liquid.

35 Just before the drum completes a revolution the can has been filled as shown at 3a and passes on to the discharge conveyer 4 and around through guards 45 and 47 on to other conveyers where the cans are capped in the usual manner.

40 I claim:—

1. A fruit and vegetable juice filling machine for cans comprising a drum rotatable on a vertical axis; a feed tank rotatable on a universal joint directly above said drum; said universal joint having an upper section provided with a shaft extension adjustably mounted off the center of the machine and at an angle causing the feed tank to converge at a certain point as it rotates; means for automatically feeding cans to said drum; a plurality of valves to hold the cans and contents in place as the same are filled through said plurality of valves equally spaced in said feed tank operable by said cans during rotation of the drum and means for conveying the cans from the drum.

2. A fruit and vegetable juice filling machine for cans comprising a drum rotatable on a vertical axis; a circular feed tank rotatable on a universal joint directly above said drum; a delivery conveyer mounted at the left front of said drum and adapted to deliver cans thereto; a plurality of valves; said universal joint having an upper section provided with a shaft extension adjustably mounted off the center of the machine and at an angle causing the feed tank as it rotates to converge at a certain point allowing said valves to contact said cans; said plurality of valves to hold the cans and contents in place as the same are filled through said plurality of valves equally spaced in said feed tank operable by said cans during rotation of the drum and a discharge conveyer mounted opposite said delivery conveyer and adapted to carry the cans therefrom.

75 3. A fruit and vegetable juice filling machine

for cans comprising a feed tank rotatable on a universal joint; a drum rotatable on a vertical axis; a delivery conveyer mounted at the left front of said drum and adapted to deliver cans thereto; said feed tank provided with a plurality of valves equally spaced therein; said universal joint having an upper section provided with a shaft extension adjustably mounted off the center of the machine and at an angle causing the feed tank as it rotates to converge at a certain point causing the top of the cans to force the valves open allowing the liquid to flow into said cans; means to hold the cans and contents in place as the same are filled during rotation of the drum and a discharge conveyer mounted opposite said delivery conveyer and adapted to carry the cans therefrom.

4. The combination in a fruit and vegetable juice filling machine for cans of a drum rotatable on a vertical axis provided with an upper and lower disc; a feed tank mounted above said drum to fill the cans; a delivery conveyer mounted at the left front of said drum; a discharge conveyer mounted opposite said delivery conveyer; said conveyers being positioned on a level with the top of the lower disc of the drum and the cans being adapted to successively move onto the drum from the delivery conveyer; an adjustable feed mechanism mounted above said delivery conveyer to keep said cans in position while being fed to said drum; said feed tank rotatable on a universal joint and provided with a plurality of valves; said universal joint having an upper section provided with a shaft extension adjustably mounted off the center of the axis and at an angle causing the feed tank to converge at a certain point as it rotates forcing the top of the cans to force the valves open allowing the liquid to flow into said cans; said cans to revolve with said drum and tank for nearly one revolution and then to successively move from the drum onto the discharge conveyer and means to hold the cans rigid during and after being filled.

5. A fruit and vegetable juice filling machine for cans comprising a frame having a base at its bottom and an auxiliary frame at its top; said frame forming a housing for a vertical drive shaft; a drum provided with an upper and lower disc fixed to and mounted at the top of said drive shaft; said drum provided with a shoulder underneath the upper disc having a driving belt mounted thereon and said belt to fit over a drive pulley connected to a drive means comprising reduction gears and motor means; a circular feed tank rotatable on a universal joint that is provided with a shaft extension adjustably mounted at an angle causing the feed tank to converge at a certain point as it rotates and said joint connecting said drum to the feed tank to rotate together; a plurality of valves equally spaced inside said feed tank and operable by the cans as the feed tank converges to contact the valves and cans that are carried in position directly underneath said valves by the drum; and means to feed said cans to the drum and means to discharge the cans from the drum.

6. A fruit and vegetable juice filling machine for cans comprising a frame having a base at its bottom and an auxiliary frame at its top; a vertical drive shaft housed in said frame; a drum provided with an upper and lower disc fixed to and mounted at the top of said drive shaft; said drum provided with a shoulder underneath the upper disc and a drive pulley with a belt mounted thereon and said pulley connected to a drive

means through reduction gears to a motor; a circular feed tank rotatable on a universal joint that is provided with an upper section adjustably mounted at its top to the auxiliary frame at an angle to tilt said feed tank and said joint connecting said drum to said feed tank to rotate to-

gether; a plurality of valves equally spaced inside said feed tank and operable by the cans placed in position directly underneath said valves by the drum; and means to feed said cans to the drum and means to discharge the cans from the drum. 5

STEFANO PITTLUGA.
